INVENTOR
Karl P. Nesselser.
By *Marie Henry*
His ATTORNEY

UNITED STATES PATENT OFFICE.

KARL P. NESSELER, OF ELIZABETH, NEW JERSEY.

MUSICAL INSTRUMENT.

Application filed November 30, 1925. Serial No. 72,133.

This invention relates to musical instruments of the piano-zither type and has as one of its objects to provide a high grade instrument at a moderate cost of construction, that can be played by any person familiar with the keyboard of an ordinary piano or organ.

It is a further feature to produce an instrument that occupies but small space and 10 can be readily moved from one place to another without difficulty.

Another aim is to avoid the use of metal so far as possible in order to secure lightness of weight and clarity of tone.

15 These and other like objects are attained by the novel construction and combination of parts hereinafter described and shown in the accompanying drawing, forming a material part of this disclosure, and in 20 which:—

Figure 1 is a fragmentary transverse sectional view of an embodiment of the invention, the section being taken on line 1—1 of Figure 2.

25 Figure 2 is a partial longitudinal sectional view taken on line 2—2 of Figure 1.

Figure 3 is a perspective view of a complete embodiment of the invention, drawn to a reduced scale.

30 Figure 4 is a front view of one of the key actuated string picking devices, shown in its normal raised position.

Figure 5 is a similar view of the same as depressed by a key.

35 Figure 6 is a side elevational view of one of the plectrums or dogs in detail.

Figure 7 is an enlarged transverse sectional view taken on line 7—7 of Figure 4.

40 As shown in Figure 3 the instrument will be seen to resemble in general appearance a small piano having a body consisting of ends 10 with a rearwardly extending portion 11, the body being raised midway its width, as at 12, and provided 45 with hinges 13 connecting a cover 14.

The cover is furnished with a sheet music support 15 and has at its front edge a downwardly extending portion 16 to cover the front part of the instrument, adjacent the 50 slanting portion 17 over the front edge 18, the body being supported by legs in the usual manner.

Below the cover, when closed, are the

half note keys 19 and whole note keys 20, both styles of keys being pivoted at the rear on a rod 21 common to all.

A fixed plate 22 is positioned below the keyboard and near its front edge is a strip of rubber or like cushion element 23, through which passes a plurality of pins 24, fixed in the plate 22 and extending into openings in the undersides of the keys to guide them in proper relation.

A sound board 25 is disposed in the lower part of the casing, forming two sound 65 chambers 26 and 27 respectively, the latter having the bottom plate of the instrument for its lower wall.

Between this wall and the sounding board 25, at the front and rear, are secured rigid 70 beams 28 having a plurality of hooks 29 disposed in two rows in uniform spaced relation, and attached to these hooks are wires 30 connecting with the music strings 31, passing from front to rear over rods 32, 75 seated on blocks 33 resting on the sounding board 25, tightening devices (not shown) of the usual type being arranged at the rear ends of the strings to permit tuning.

80 A rigid metal bar 34 is set in the plate 22, parallel with the front, this being secured by a flange 35 and cut away to receive a plurality of square sectioned plungers 36 having cylindrical stems 37 slidable in openings in the bar 34 and making contact 85 with their rounded ends with blocks 38 secured to the undersides of each key.

These stems are encircled by expansion springs 39 which abut at their respective ends against pins 40 passing transversely 90 through the ends of the stems and recesses in the bar 34.

The plungers 36 extend downwardly between and adjacent pairs of the strings 31, and are slotted through on all sides, as at 95 43 and 44, and also recessed longitudinally in their rear sides.

Flat strips 45 are fixed to the bar 34 extending downward within the recesses in the rear side of the plungers and set in 100 the slots 43, at right angles to the slots 44, other pins 46 entering the slots 44, other pins 41 extending oppositely outward to move in recesses 42 formed in the bar 34.

105 In the slots 43, at right angles to the slots 44, are opposed pairs of plectrums 47,

generally anchor-shaped and pivoted on pins 48, the upper extending points of the plectrums being pressed outwardly by springs 49 secured at 51 to the front sides of the plungers:

The inner edges of the plectrums present opposed cam surfaces 52 engageable with the pins 46 when the plungers are in a raised position, and thereafter permit the plectrums to recede so that upon releasing the key the plectrums engage and snap the adjacent strings, due to the action of the springs 39, in a manner similar to hand picking.

Although the foregoing is generally descriptive of the preferred embodiment of the invention, it is not desired to be restricted to the exact construction, as changes

may be made within the scope and spirit of the appended claim.

Having thus described my invention, I claim:—

A key operated stringed musical instrument comprising a casing having a key board, a plurality of strings extending in a horizontal plane transversely in said casing below the key board, a plunger for each key, pairs of plectrums pivoted in opposed relation in each plunger, said plectrums engaging the strings on their upward movement, means for actuating said plungers and means to release said plectrums upon raising said plungers.

In witness whereof I have affixed my signature.

KARL P. NESSELER.
